ROTARY COMPRESSOR

Jacob J. Merch, Pert Credit, Ontario, Canada

Application February 19, 1934, Serial No. 711,929

2 Claims. (Cl. 230—140)

This invention relates to mechanism particularly adapted for use as a rotary compressor used to deliver compressed air or a compressed gaseous fuel mixture to means for utilizing it in the generation of power, and my object is to devise simple and efficient means for this purpose involving no reciprocating parts.

I attain my object by means of the constructions hereinafter described and illustrated in the accompanying drawings in which

Fig. 1 is a longitudinal section of my improved compressor;

Fig. 2, a sectional elevation showing the intake port;

15 Fig. 3, a section on the line 3—3 in Fig. 1;

Fig. 4, a plan of the underside of the ring 19 in Fig. 1;

Fig. 5, a side elevation of the ring 19 in Fig. 1; and

20 Fig. 6, an elevation of the adjusting means between the stationary casing and the shaft.

In the drawings like numerals of reference indicate corresponding parts in the different figures.

25 Referring to the drawings, 1 is a hollow stationary shaft which is mounted in a stationary casing 2. Rotatably mounted on the shaft is the rotary casing 3. This casing is formed with a hub 4 in which the reduced end of the shaft 1 is journaled and which in turn is journaled within the sleeve 5 of the stationary casing.

The shaft 1 is formed with an eccentric portion 6 of reduced diameter on which is rotatably mounted the cylindrical piston disk 7 which at 35 one portion of its periphery fits close to the inner periphery of the rotary casing 3. This piston disk has a plurality of cylindrical recesses formed therein on axes parallel to the axis of the shaft in which recesses are journaled the spools 9 each having an arc of its periphery exposed at the periphery of the disk.

40 Each spool has a pocket 10 formed therein adapted to receive a vane 11 hinged within the rim 12 of the rotary casing. Preferably I employ for this purpose a hollow journal 13 having a bearing in the rim. The hollow communicates with a port 14 formed through one face of the vane.

45 Intermediate of the vanes a corresponding number of radial passages 15 are formed in the piston disk adapted to successively communicate with a port 16 formed in the part 6 of the hollow shaft.

50 One end of the hollow journal of each vane

11 is in communication with a radial passage 17 formed in one end of the rotary casing 3.

5 Radial passages 21 in the stationary casing are in communication with an annular passage 18 in a ring 19 mounted on the stationary casing adjacent the shaft 1, which ring bears against the rotary casing. This ring 19 has a port 20 formed in its face adjacent the rotary casing which, as the casing rotates comes successively into communication with the axially directed 10 inner ends of the passages 17. Thus every time a passage 17 is in communication with the port 20 any fluid passing therefrom will flow to all the passages 21.

15 The ring 19 is held from rotation by the pins 22 connected therewith and entering recesses in the hub of the stationary casing 2. In each recess is positioned a thimble 23 having a hole in its end in which the pin fits. A coil spring 24 fitted between the thimble and the ring 19 serves to hold the latter tightly against the hub of the rotary casing 3 in which the inner ends of the passages 17 are formed.

20 The passages 21 in the stationary casing communicate respectively with ports 25 formed in the rim 26 of the stationary casing 2 and opening into the annular chamber 33 provided with the outlets 37.

25 To make an air tight fit between the contacting sides of the rotary casing 3 and the piston disk 7, I provide a plate 30 at one side thereof bearing against the side of the piston disk and having a hub 31 fitting in an annular recess in the hub 4. A coil spring or springs 32 fitted in the recess press the plate 30 against the disk 7.

30 It is desirable to be able to vary the angular position of the stationary casing with its passages and ports relative to the compressor formed by the rotary casing 3 and piston disk 7. For this purpose I secure to the end of the stationary 40 shaft 1 a segmental worm gear 38. With this meshes a worm 39 journaled on the hub of the stationary casing 2.

35 Other specific details are unimportant and may be varied considerably without departing from the spirit of my invention.

The end of the hollow shaft may be connected with any suitable carburettor if a gaseous fuel mixture is to be compressed or may simply open to the atmosphere.

40 The mode of operation is substantially as follows assuming the rotary parts are driven in the direction of the arrow in Fig. 1 as by a pulley 36 secured to the shaft 4. As the piston disk and rotary casing 3 rotate about the hollow shaft 1,

the radial passages 15 are successively brought into alinement with the inlet port 16. Air, or fuel mixture, can then flow into the space between two vanes 11, which space constantly enlarges till the two vanes in question reach a position in which they are equidistant from the point of contact of the piston disk with the inner periphery of the rotary casing. The particular passage 15, through which the fluid has been flowing is then out of communication with the inlet port and compression begins through the port 14 in the forward face of the rearward of the vanes between which the fluid is trapped and continues until the corresponding radial passage 17 comes into communication with the port 20 in the ring 19.

Immediately the compressed fluid flows from the compressor through the passage 17 in communication with the port 20, through the port and into the groove 18, through the groove to each of the radial passages 21, and thence to the ports 25, which are in communication with the chamber 33 from which the compressed fluid may be discharged for use.

From the above description it will be seen that I have devised a rotary compressor in which all the parts are rotary and from which a substantially even and constant flow of compressed gaseous fluid may be obtained.

What I claim as my invention is:

1. A rotary compressor comprising a rotary cylindrical casing; a cylindrical piston disk rotatably mounted in and eccentric to the casing; a plurality of vanes hingedly connected with the internal periphery of the cylindrical casing; a plurality of spools journaled in the piston disk on axes parallel to that of the disk, each having an arc of its periphery disclosed at the periphery of the disk and each disk having a pocket slidably receiving one of the vanes; a stationary hollow shaft on which the piston disk rotates, the shaft having a radial port therein and the piston disk

radial inlet passages adapted successively to communicate with said port, the said vanes each having an exit passage extending through one face thereof, and through its hinge in a direction parallel to its axis; radial conduits in the casing communicating at their outer ends with said passages; a stationary conduit for compressed air; and a stationary part concentric with the rotary casing and having a chamber therein with which the stationary conduit communicates, said chamber having a port therein with which the inner ends of the radial conduits successively communicate.

2. A rotary compressor comprising a rotary cylindrical casing; a cylindrical piston disk rotatably mounted in and eccentric to the casing; a plurality of vanes hingedly connected with the internal periphery of the cylindrical casing; a plurality of spools journaled in the piston disk on axes parallel to that of the disk, each having an arc of its periphery disclosed at the periphery of the disk and each disk having a pocket slidably receiving one of the vanes; a stationary hollow shaft on which the piston disk rotates, the shaft having a radial port therein and the piston disk radial inlet passages adapted successively to communicate with said port, the said vanes each having an exit passage extending through one face thereof, and through its hinge in a direction parallel to its axis; radial conduits in the casing communicating at their outer ends with said passages; a stationary radial conduit for compressed air; a stationary part concentric with the rotary casing and having a chamber therein with which the stationary radial conduit communicates, said chamber having a port therein with which the inner ends of the radial casing conduits successively communicate; and an annular chamber exterior to the rotary casing and with which the stationary radial conduit connects.

JACOB J. MORCH.
